UNITED STATES PATENT OFFICE

SAMUEL L. HIGHFILL, OF WINFIELD, KANSAS, AND ROBERT P. MAYS, OF CLEVELAND,
OKLAHOMA

UNDERREAMER

Application filed February 26, 1927. Serial No. 171,261.

Our invention relates to well drilling tools and more particularly to improvements in underreamers.

It is an object of our invention to provide an underreamer having a releasable locking means associated with the expansion means for the cutters, whereby the cutters and expansion means will be firmly maintained in operating position and yet may be readily disassembled and which is especially adapted for use with the underreamer shown in our co-pending application, filed January 11, 1927, Serial Number 160,427.

A further object of the invention is to provide a device of the above-mentioned character which is simple and durable in construction, reliable and efficient in operation and inexpensive to manufacture.

Other objects and advantages of the invention will be apparent during the course of the following description.

In the accompanying drawings, forming a part of this specification and in which like numerals are employed to designate like parts throughout the same,

Fig. 1, is a longitudinal sectional view of an underreamer embodying our invention,

Fig. 2, is an enlarged longitudinal sectional view of the same,

Fig. 3, is a view similar to Fig. 2, showing the mandrel depressed,

Fig. 4, is a detail perspective view of the clutch mechanism showing the parts in separate relation, and,

Fig. 5, is a cross sectional view taken on lines 5—5 of Fig. 3.

In the drawings, wherein for the purpose of illustration, we have shown a preferred embodiment of our invention, the numeral 5 denotes a reamer body having a longitudinal bore 6, enlarged at its lower end to provide a socket 7, to receive the shanks 8 of the rockable cutters 9, which are suspended from the wall of the socket by lugs 10, adapted to fit slots 11 formed in the wall. The upper end of the body is provided with a tapered screw-threaded recess 12 to receive the screw-threaded nipple 13 depending from the cap 14, by means of which the reamer is connected with the usual string of drilling tools.

A mandrel 15 is disposed in the bore 6 of the reamer body having its lower end disposed intermediate the inner faces of the cutters, which are provided with longitudinal grooves 16 to receive the mandrel and the upper ends of the cutters contact with the mandrel which serves as a fulcrum for the cutters which automatically move to a collapsed position when the expansion wedge 17, connected to the lower end of the mandrel is withdrawn. This construction is identical with the construction shown and claimed in our co-pending application, above referred to and is merely shown for the sake of clearness in understanding the present invention and it is to be understood that the showing of this construction is not intended to limit the use of the present invention to a construction of this character, as the same may be used with constructions of various types.

Referring more particularly to our present invention an expansion spring 18 is mounted on the mandrel 15 within the bore of the reamer body having its lower end seated on the shoulder 19 at the lower end of the bore and its upper end bearing against the clutch collar 20, slidably mounted on the upper end of the mandrel. A key 21, fitted in the opening 22, in the side of the collar enters a longitudinal keyway 22' formed in the mandrel, connecting the collar and mandrel together. The extreme upper end of the mandrel is screw-threaded as at 23 and terminates in a reduced square head 24. A stud 25 having a screw-threaded bore 26, receives the upper end of the mandrel and its lower end is provided with a series of spaced notches 27, adapted to receive the humps or teeth 28, formed around the upper edge of the clutch collar, and the expansion spring 18 forces the clutch collar upwardly into tight engagement with the notches of the stud, at the same time exerting an upward thrust upon the mandrel, causing the wedge block to expand and firmly hold the cutters in operative position.

The trip mechanism for holding the mandrel depressed while inserting the reamer into the well hole, consists of a cross bar 29 which extends transversely through open-

ings 30 in the stud 25, and is provided centrally of its lower edge with a recess 31, to receive the square head 24 of the mandrel when the latter is screwed into the stud, locking the bar against undue transverse movement. The bar moves longitudinally of the body in the longitudinal slots 32, extending between the bore of the body and the longitudinal grooves 33, formed in opposite sides 10 of the body. A trip 34 is mounted on each end of the cross bar being slidably connected therewith by transverse pins 35, extending through slots 36 in the bar. The trips are movable longitudinally in the grooves 33 and 15 the surface of the grooves at their lower portions are on a plane nearer the longitudinal axis of the body, than the upper portions, so that when the trips are seated in the lower ends of the grooves they will lie within the circumference of the body. The grooves are 20 of such length that the wedge 17 may be withdrawn to clear the bottom of the cutters to permit turning of the mandrel. When the wedge is withdrawn, for the purpose of removing the mandrel, it is held in this position by a removable pin 34 extending transversely of the body, which intersects the bore 6 and serves as a stop for the upper end of the stud.

From the foregoing, it is seen that the clutch collar is held in tight engagement with the stud, through the tension of the spring, releasably locking the mandrel against rotary movement. To remove the cutters from the socket it is necessary to first remove the mandrel and when the mandrel is withdrawn, so the wedge clears the bottom of the cutters, the turning of the mandrel under pressure will release the clutch, permitting the mandrel to be unscrewed from the stud and withdrawn from the body, thereby permitting ready removal of the cutters. Also the removal of the mandrel will release the cross bar of the trip mechanism and upon removal 45 of one of the trips, the mechanism may be readily disassembled if desired.

It is to be understood that the form of our invention herewith shown and described is to be taken as a preferred example of the same and that certain changes in the shape, size 50 and arrangement of the parts may be made without departing from the spirit of the invention or the scope of the subjoined claims.

Having thus described our invention, we 55 claim:—

1. A tool of the character described comprising a body, movable cutters, actuating means for said cutters and a clutch associated with said actuating means for normally holding it against removal, said actuating means being releasable upon rotation under pressure.

2. A tool of the character described comprising a body, movable cutters, actuating 35 means for said cutters removably mounted

within said body and a clutch associated with said actuating means normally holding same against removal, said actuating means being releasable upon rotation.

3. A tool of the character described comprising a body, movable cutters, a trip mechanism, actuating means for said cutters removably connected with said trip mechanism and a clutch normally holding said actuating means against removal, said clutch being releasable upon rotation of the actuating means under pressure.

4. A tool of the character described comprising a body, movable cutters, a trip mechanism, spring controlled actuating means for said cutters removably connected with said trip mechanism and a clutch carried by said actuating means for locking said means against removal, said clutch being releasable upon rotation of the actuating means under pressure.

5. A tool of the character described comprising a body, movable cutters, actuating means for said cutters removably mounted in said body, a clutch for normally locking said actuating means against removal and a spring for controlling said actuating means and clutch, said actuating means being releasable upon rotation under pressure.

6. A tool of the character described comprising a body, movable cutters, expanding means for said cutters detachably mounted in said body, a clutch collar for normally locking said expanding means against detachment slidably mounted on and connected with said expanding means and a spring for controlling said expanding means and clutch collar.

7. A tool of the character described comprising a body, movable cutters, expanding means for said cutters mounted in said body, a clutch member slidably mounted in said body adapted to detachably receive the upper end of said expanding means, a clutch collar slidably mounted on and connected with said expanding means adapted to co-act with said clutch member and a spring for controlling said expanding means and clutch collar.

8. A tool of the character described comprising a body, movable cutters, a stud slidably mounted in said body, expanding means for said cutters mounted in said body and detachably connected with said stud, a clutch collar slidably mounted on and connected with said expanding means adapted to co-act with said stud and a spring for controlling said expanding means and clutch collar.

9. A tool of the character described comprising a body, movable cutters, a stud slidably mounted in said body, a trip mechanism consisting of a cross bar extending transversely through said body and stud, expanding means for said cutters mounted in said body and detachably connected with said stud, a clutch collar slidably mounted on said

expanding means adapted to co-act with said stud to normally hold said expanding means against detachment, and a spring for controlling said expanding means and clutch collar.

5 10. A tool of the character described comprising a body, movable cutters, a trip mechanism, actuating means for said cutters and a clutch detachably connecting said actuating means with said trip mechanism, said clutch being releasable upon rotation of the actuating means under pressure.

10 15. A tool of the character described comprising a body, movable cutters, a clutch member slidably mounted in said body, a trip mechanism consisting of a cross bar extending transversely through said body and clutch member having a notch in its lower edge, means for actuating said cutters detachably connected with said clutch member and having engagement with said notch, and a clutch collar carried by said actuating means adapted to normally hold said means against removal.

20 25. In testimony whereof we affix our signatures:

SAMUEL L. HIGHFILL.
ROBERT P. MAYS.
